ABSTRACT OF THE DISCLOSURE

New alkyl sulfonic acid esters of 1,3,2-oxazaphosphacyclic compounds of formula I

I

These new compounds produce a high immunosuppressing activity in humans.

The present invention is related to alkyl sulfonic acid esters of 1,3,2-oxazaphosphacyclic compounds which produce a high immunosuppressing activity. The invention is further related to process for the production thereof and to pharmaceutical preparations containing the same.

The new compounds according to the present invention correspond to the formula I

I

wherein R is a halogen atom, preferably a chlorine atom, or a lower alkyl sulfonic acid group having a straight or branched lower alkyl chain with 1 to 6 carbon atoms, R1 and R2 are hydrogen or a lower alkyl group with 1 to 4 carbon atoms which alkyl group may be substituted with a halogen atom, preferably a chlorine atom, or with a lower alkyl sulfonic acid group having a straight or branched lower alkyl chain with 1 to 6 carbon atoms, R1 and R2 being identical or different from each other and there being present in the molecule of formula I at least one such lower alkyl sulfonic acid ester group, and alk represents a straight or branched alkylene group with 2 or 3 carbon atoms in the chain and, if branched, with a total of 3 or 4 carbon atoms, X represents oxygen or sulphur, Z represents a hydrogen atom or a lower alkyl group having from 1 to 4 carbon atoms and m is 2 or 3.

Because of their favourable compatibility those compounds of formula I are preferred, wherein X is oxygen. Because of their high immunosuppressing activity, those compounds are particularly preferred which have the formula II

II

2

wherein R, R1, R2 and alk have the same meaning as in formula I. Among these compounds of formula II the compounds of formula III

5

III

are particularly preferred, wherein R7 is an unsubstituted lower alkyl group having from 1 to 6 carbon atoms in a straight or branched chain and alk is the group

and R7 is the methyl group.

It is surprising that the compounds of formula I show a strong immunosuppression which activity has not been known up to now with alkyl sulfonic acid esters. The compounds of the following Examples 1 and 3-6 in particular produce a substantial or even complete suppression of antibody formation until the 7th day after the administration of the antigen. The immunactivity in connection with the Brucella immunisation of rats is used to demonstrate this activity.

The new compounds of formula I are produced by using methods known as such. The process for the production of the compounds according to the present invention comprises

(A) Subjecting a compound of formula IV

IV

wherein R3 has the same meaning as R in formula I or is a hydroxy group, R4 has the same meaning as R1 in formula I or is a lower alkyl group having from 1 to 4 carbon atoms and being substituted by a hydroxy group, alk and X have the same meaning as in formula I and X1 is a halogen atom, preferably a chlorine atom, to react with a compound of formula V

V

wherein R5 has the same meaning as R4 in formula IV and Z and m have the same meaning as in formula I, or

(B) Subjecting a compound of the general formula VI

VI

wherein R3 and R4 have the same meaning as in formula IV and alk has the same meaning as in formula I, to react with a compound of formula VII

VII

wherein X_1 has the same meaning as in formula IV, R_5 has the same meaning as in formula V and X, Z and m have the same meaning as in formula I, or

(C) Subjecting a compound of formula VIII

VIII

wherein R_5 has the same meaning as in formula V and X, Z , alk and m have the same meaning as in formula I, to reaction with a compound of formula IX

wherein R_3 has the same meaning as in formula IV, and converting the hydroxy groups in the resulting compounds of formula X

X

wherein one or several of the R_3, R_4 and R_5 groups represent or carry a hydroxy group, into a halogen atom or the group $-\text{OSO}_2\text{R}_6$, R_6 being a straight or branched lower alkyl group having from 1 to 6 carbon atoms, by subjecting said hydroxy compounds to reaction with a halogenating agent or a sulfonic acid halogenide

R_6 having the same meaning as above and Hal being a halogen atom, preferably a chlorine atom and, if desired, exchanging one or several halogen atoms in the resulting compounds of formula X, wherein none of the R_3, R_4 and R_5 groups represent or carry a hydroxy group and one or several of the R_3, R_4 and R_5 groups represent or carry a halogen atom, against the group $-\text{OSO}_2\text{R}_6$, by subjecting such a compound of formula X to reaction with a compound of formula XI

XI

wherein R_6 has the above given meaning and Me is a metal of the first or second main or sub-group of the periodic system of elements, and preferably is silver.

The reactions are preferably carried out in the presence of an inert solvent such as acetonitrile or a lower halogenated hydrocarbon such as chloroform or methylene chloride, or in an ether such as diethylether or dioxane, or in an aromatic hydrocarbon such as benzene or toluene. The reaction is carried out at an elevated temperature ranging from room temperature to the boiling point of the reaction mixture.

The reactions are preferably carried out in the presence of an acid binding agent. The acid binding agent should be present in an amount ranging from 1 to 2 mole equivalents. There are numerous known alkaline compounds which may be used as acid binding agents such as alkali metal and alkaline earth metal carbonates and bicarbonates and particularly tertiary amines such as triethylamine and pyridine.

Halogenating agents for exchanging aliphatically bound hydroxy groups against halogen atoms are also known. Useful for this purpose are for instance the phosphorous halides such as phosphorous trichloride or tribromide, phosphorous pentachloride, phosphorous oxychloride or oxybromide, the sulfurous and sulfonic acid halides such as sulfurylchloride and thionylchloride, or phosgene. Thionylchloride is most preferably used in view of the ease to handle it.

Usual carrier products for pharmaceutical preparations, which may contain a compound according to formula I as active agent, are pharmacologically inert prod-

ucts as they are known for the production of tablets, dragees, suppositories and injection solutions.

The following examples further illustrate the present invention without however limiting the same thereto. The compounds according to the present invention are characterized by their infrared spectra and show characteristic

$P=O$ —bands at 1188 to 1275 cm^{-1} ,
 $-\text{C}-\text{SO}_3-\text{C}-$ bands at 1330 to 1376, 1165 to 1175, 905 to 975 and 787 to 805 cm^{-1} ,
 $-\text{P}-\text{O}-\text{C}-$ bands at about 1050 and 975 cm^{-1} , and
 $\text{NH}-$ bands at 3200 to 3300 cm^{-1} .

EXAMPLE 1

2-(2-Methylsulfonyloxyethylamino)-3-(2-chloroethyl)-tetrahydro-2H-1,3,2-oxazaphosphorine-2-oxide

A solution of 113.2 g. of chloro-3-(2-chloroethyl)-tetrahydro-2H-1,3,2-oxazaphosphorine-2-oxide in 360 cc. of anhydrous dioxane are added dropwise at 15-18° C. to a solution of 31.6 g. of ethanamine and 57 g. of triethylamine in 300 cc. of anhydrous dioxane. Stirring is continued for one hour at 30-35° C. Thereafter, the precipitated triethylamine hydrochloride is filtered off with suction and the filtrate is evaporated in a water jet vacuum. The residue is washed 3 to 4 times with each 100 cc. of ether. After drying in a high vacuum, the resulting 2-(2-hydroxyethylamino)-3-(2-chloroethyl)-tetrahydro-2H-1,3,2-oxazaphosphorine-2-oxide is obtained as a faintly yellow oil.

Yield: 121.3 g. (97% of the theoretical).

A solution of 121.3 g. (0.5 mole) of the above compound and 50.6 g. (0.5 mole) of triethylamine in 320 cc. of dioxane is prepared. This solution is added to a solution of 57.3 g. (0.5 mole) of methane sulfonic acid chloride in 340 cc. of dioxane dropwise within 30 minutes at 26-28° C. Thereafter, 150 cc. of ether are added and stirring at 10° C. is continued for another 30 minutes. The precipitated triethylamine hydrochloride is filtered off with suction and the filtrate is evaporated at 30-35° C. in a water jet vacuum. Ether is added to the oily residue which crystallizes while standing in an ice box after seeding. The product is purified by dissolving it in ethanol and adding ether to the ethanolic solution and allowing to stand in the ice box. The product is obtained in nice colorless crystals upon extraction in a soxhlet apparatus with a mixture of methylene chloride and ether.

Yield: 111 g. (69% of the theoretical).

F.: 81-82° C.

EXAMPLE 2

2-(3-Methylsulfonyloxypropylamino)-3-(2-chloroethyl)-tetrahydro-2H-1,3,2-oxazaphosphorine-2-oxide

A solution of 37.4 g. of 2-chloro-3-(2-chloroethyl)-tetrahydro-2H-1,3,2-oxazaphosphorine-2-oxide in 140 cc. of anhydrous dioxane is added dropwise to a solution of 12.95 g. of propanolamine-1,3 and 17.3 g. of triethylamine in 140 cc. of anhydrous dioxane dropwise with stirring within 50 minutes at a temperature ranging from 15-18° C. The precipitated triethylamine hydrochloride is filtered off with suction and the filtrate is evaporated in a water jet vacuum. The residue is washed several times with ether. Upon drying in a high vacuum, the resulting 2-(3-hydroxypropylamino)-3-(2-chloroethyl)-tetrahydro-2H-1,3,2-oxazaphosphorine-2-oxide is obtained as a highly viscous clear oil.

Yield: 38.6 g. (86% of the theoretical).

A solution of 38.6 g. of the above compound and 15.5 g. of triethylamine in 120 cc. of anhydrous dioxane is added to a solution of 17.2 g. of methane sulfonylchloride in 120 cc. of anhydrous dioxane dropwise with stirring within 30 minutes at a temperature ranging from 28-30° C. The separated triethylamine hydrochloride is filtered off with suction and the filtrate is evaporated in a water jet vacuum. The oily residue is dissolved in water and

purified by means of the ion exchanger Duolit (A 102). Anhydrous ether is added to the colorless oil and the mixture is cooled in an ice-bath and scratched from time to time. Thus, the product crystallizes. The crystals are recrystallized from ethyl acetate.

Yield: 13.9 g.

F.: 59-60° C.

EXAMPLE 3

2-(2-Ethylsulfonyoxyethylamino)-3-(2-chloroethyl)-2H-tetrahydro-1,3,2-oxazaphosphorine-2-oxide

A solution of 24.3 g. of 2-(2-hydroxyethylamino)-3-(2-chloroethyl)-2H-tetrahydro-1,3,2-oxazaphosphorine-2-oxide (prepared as described in Example 1) and 10.1 g. of triethylamine in 60 cc. of anhydrous dioxane is added to a solution of 12.9 g. of ethane sulfonylchloride in 70 cc. of anhydrous dioxane dropwise with stirring within 20 minutes at a temperature ranging from 28-30° C. The reaction mixture is allowed to stand for 1 hour. Thereafter, the precipitated triethylamine hydrochloride is filtered off with suction. The solvent is evaporated in a vacuum and the resulting oily residue is purified by first extracting in a perforator with ether and then with a 2:1 mixture of methylene chloride and ether. The first ethereal extract is discarded. The solvents are evaporated from the methylene chloride/ether extracts and the resulting product crystallizes upon standing in the ice-box. The compound is recrystallized from methanol/ether.

Yield: 10 g.

F.: 62-64° C.

EXAMPLE 4

2-(2-Propylsulfonyoxyethylamino)-3-(2-chloroethyl)-2H-tetrahydro-1,3,2-oxazaphosphorine-2-oxide

A solution of 24.3 g. of 2-(2-hydroxyethylamino)-3-(2-chloroethyl)-2H-tetrahydro-1,3,2-oxazaphosphorine-2-oxide (prepared as described in Example 1) and 10.1 g. of triethylamine in 170 cc. of anhydrous dioxane is added dropwise to a solution of 14.3 g. of n-propylsulfonylchloride in 70 cc. of anhydrous dioxane dropwise with stirring and cooling within 15 minutes at a temperature ranging from 28-30° C. Stirring is continued for a short period of time at 30° C. Thereafter, 60 cc. of anhydrous ether are added, the mixture is cooled to 10° C. and stirring is continued for another half hour. The separated triethylamine hydrochloride is filtered off with suction and the filtrate is filtered over activated charcoal and evaporated in a water jet vacuum. The oily residue is extracted in a perforator with a 1:1 mixture of ether and methylene chloride. The extract is allowed to stand in the ice-box and is scratched several times thus causing the desired product to crystallize. The crystals are recrystallized from the same solvent mixture.

Yield: 14 g.

F.: 78° C.

EXAMPLE 5

2-(2-Isopropylsulfonyoxyethylamino)-3-(2-chloroethyl)-2H-tetrahydro-1,3,2-oxazaphosphorine-2-oxide

A mixture of 24.3 g. of 2-(2-hydroxyethylamino)-3-(2-chloroethyl)-2H-tetrahydro-1,3,2-oxazaphosphorine-2-oxide (prepared as described in Example 1) and 10.5 g. of triethylamine in 75 cc. of dioxane are added to a solution of 14.3 g. of isopropane sulfonylchloride in 70 cc. of dioxane dropwise within 25 minutes at a temperature ranging from 28-30° C. The separated triethylamine hydrochloride is filtered off with suction. The solvent is evaporated in a water jet vacuum and the oily residue is washed with ether in a perforator for 2 hours. Thereafter, it is extracted twice with a mixture of methylene chloride and ether. The extracts are filtered over activated charcoal and evaporated. Thus, a clear yellowish and

highly viscous oil is obtained which is purified chromatographically over a column of silica gel in methylene chloride.

Yield: 16.4 g. (47% of the theoretical).

n_{D20}^2 : 1.4927.

EXAMPLE 6

2-(2-n-Pentylsulfonyoxyethylamino)-3-(2-chloroethyl)-2H-tetrahydro-1,3,2-oxazaphosphorine-2-oxide

10 A solution of 24.3 g. of 2-(2-hydroxyethylamino)-3-(2-chloroethyl)-2H-tetrahydro-1,3,2-oxazaphosphorine-2-oxide (prepared as described in Example 1) and 10.5 g. of triethylamine in 90 cc. of dioxane is added to a solution of 17.1 g. of n-pentylsulfonylchloride in 75 cc. of dioxane dropwise with thorough stirring and cooling such that the temperature does not rise above 35° C. Stirring is continued for another half an hour. The precipitated triethylamine hydrochloride is filtered off with suction and the filtrate is evaporated in a water jet vacuum. The resulting oil is dissolved in chloroform and washed with dilute hydrochloric acid, a sodium bicarbonate solution and water. The thus treated solution is again evaporated. The residue is extracted with ether in a perforator. The ethereal extract is allowed to stand in an ice-box whereupon the desired final product crystallizes. It is recrystallized from ether.

Yield: 10.5 g. (27.8% of the theoretical).

F.: 59-60° C.

EXAMPLE 7

30 The following recipe is used for the production of 100,000 dragées containing each 50 mg. of the active compound according to the present invention:

	Kg.
35 Compound according to Example 1	5.000
Corn starch	4.000
Polyvinylpyrrolidone	0.060
Talcum	0.575
Magnesium stearate	0.250
	14.000

40 The crystalline active compound is passed together with 3 kg. of corn starch through a sieve having a mesh size of 1 mm. The products are thoroughly mixed and a paste is formed with a 10% solution of the polyvinylpyrrolidone in isopropanol. The moist product is granulated by passing it through a sieve having a mesh size of 3 mm. It is then dried and ground to a particle size of 1 mm. Finally, the remaining auxiliary products of the above recipe are sieved and thoroughly admixed and 100,000 dragées are pressed each weighing 140 mg., having a diameter of 7 mm. and a camber diameter of 6 mm. The resulting kernels are coated in manner known per se by first applying a lager resistant to the gastric juices giving each 45 kernel a weight of 170 mg., then applying a cover until a kernel weight of 205 mg., smoothing the surfaces of the kernels until a kernel weight of 215 mg. and thereafter applying color layers up to a kernel weight of 240 mg. Finally, the coated kernels are rendered glossy by 50 sieving and thoroughly admixed and 100,000 dragées are pressed each weighing 140 mg., having a diameter of 7 mm. and a camber diameter of 6 mm. The resulting kernels are coated in manner known per se by first applying a lager resistant to the gastric juices giving each 55 kernel a weight of 170 mg., then applying a cover until a kernel weight of 205 mg., smoothing the surfaces of the kernels until a kernel weight of 215 mg. and thereafter applying color layers up to a kernel weight of 240 mg. Finally, the coated kernels are rendered glossy by 60 applying a layer of hard wax.

EXAMPLE 8

65 A dry mix of active compound and sodium chloride is filled into glass to be for the production of injection solution. In the last step of purification by recrystallization of the active compound according to Example 1, the solution thereof is passed through a filter holding back germs. The further processing is effected under aseptic conditions. The crystallized compound is separated by centrifugation and dried and held in an atmosphere of ethylene oxide. A sample is taken and checked for purity and sterility. After clearance of further processing is obtained, the compound is mixed with sterile sodium chloride p.a. in a weight proportion of 100 to 45 under aseptic conditions,

thus producing a finely divided homogenous mix. Another sample is taken and tested for its content in active compound, for sterility and freedom of pyrogenous compounds. After clearance of further processing, 145 mg. of the mix are filled into flasks of 10 ml. each under aseptic conditions and in an atmosphere of nitrogen. The flasks are closed with aseptic stoppers of butyl caoutchouc. The final check is made in accordance with the recommendations of the section "Testing for Good Quality and Sterility" of the German Federal Health Administration. In order to produce injection solutions, 5 cc. of water purified for injection solutions are added to the content of a flask which is dissolved therein.

The compounds according to the present invention are useful in the treatment of autoimmune diseases (autoaggressive diseases), such as autoimmune haemolytic anaemia, lupus erythematoses and polyarteritis nodosa. The compounds are preferably applied in a daily dose ranging from 2 to 4 mg./kg. A particularly useful and therefore most preferred compound is that of Example 1.

What we claim is:

1. An alkyl sulfonic acid ester of 1,3,2-oxazaphosphorinic cyclic compounds of the formula III

30

wherein R_7 is a straight or branched lower alkyl group having from 1 to 6 carbon atoms and alk represents a straight or branched alkylene group having 2 or 3 carbon atoms in the chain and, if branched, having a total number of 3 or 4 carbon atoms.

5 2. A compound according to claim 1 wherein alk is

10 3. A compound according to claim 1 wherein alk is $—\text{CH}_2\text{CH}_2—$ and R_7 is methyl or ethyl, or alk is

15 and R is methyl.

4. 2-(2-Methylsulfonyloxyethylamino)-3-(2-chloroethyl)-tetrahydro-2H-1,3,2-oxazaphosphorine-2-oxide.

UNITED STATES PATENT OFFICE
CERTIFICATE OF CORRECTION

Patent No. 3,828,090

Dated August 6, 1974

Inventor(s) Herbert Arnold et al.

It is certified that error appears in the above-identified patent and that said Letters Patent are hereby corrected as shown below:

Col. 3, Line 62, "mines" should read -- amines --.

Col. 6, Line 5, " n_D^{20} " should read -- n_D^{20} --.

Col. 7, Claim 1, the structural formula should read as follows:

Signed and sealed this 3rd day of December 1974.
